UNITED STATES PATENT OFFICE.

CLEMENT CRESSON, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,891, dated May 8, 1883.

Application filed February 7, 1883. Term of patent 14 years.

To all whom it may concern:

Be it known that I, CLEMENT CRESSON, a citizen of the United States, residing in the city and county of Philadelphia, and State of Pennsylvania, have invented and produced a new and original Design for Fringe, of which the following is a specification, reference being had to the accompanying drawing, forming part thereof.

10 The drawing represents in front elevation a fringe which illustrates my design, and in which A are spirally-fluted cylindrical pendants, ornamented with balls B, and attached to any suitable heading, C.

I claim—

- 15 1. A design for a fringe, consisting of a heading, and of spirally-fluted cylindrical pendants, as shown and described.
2. A design for a fringe, consisting of a heading, and of spirally-fluted cylindrical pendants ornamented with balls, as shown and described.

In testimony whereof I have hereunto signed my name this 29th day of January, A. D. 1883.

CLEMENT CRESSON.

In presence of—

J. BONSALL TAYLOR,
JOHN JOLLEY, Jr.
